UNITED STATES PATENT OFFICE

STUART H. SWALLOW, OF PROVIDENCE, RHODE ISLAND, ASSIGNEE TO W. H. COE MANUFACTURING COMPANY, OF PROVIDENCE, RHODE ISLAND, A CORPORATION OF RHODE ISLAND

METALLIC LEAF APPLYING DEVICE

Application filed November 7, 1928. Serial No. 317,843.

This invention relates to improvements in a metallic leaf applying device and the package roll therefor; and has for its object to provide in such a device a shaft on which the package roll is mounted and to provide the core of this roll with one or more openings to be engaged by a drive member fixed on the shaft by means of which the roll is caused to be driven in time with the shaft.

10 With these and other objects in view, the invention consists of certain novel features of construction, as will be more fully described, and particularly pointed out in the appended claim.

15 In the accompanying drawings:

Fig. 1 is a perspective view of an improved metallic leaf applying device.

20 Fig. 2 is a central section thru the applying device showing my improved package roll mounted on and fixed to the shaft in the device with its leaf metal backing strip or ribbon leading to and about the depositing roll.

25 Fig. 3 is an edge view of the device partly in section showing a metallic leaf package roll mounted therein and pressed into engagement with the shaft drive member by a flat spring.

30 Fig. 4 is a perspective view of the drive member fixed to the shaft.

Fig. 5 is a face view of the metal strip package roll having a plurality of openings spaced about the face of its core to selectively receive the drive member.

35 Fig. 6 is a diagrammatic view illustrating the two extreme positions of the depositing roll relative to the center line thru the applying device at the start and finish of a depositing stroke wherein the surface of the roll has been caused to travel from a point in advance of this line to a point back of this line thereby necessitating a backward rotation of the roll in order to bring the starting point again into proper position to start another 40 depositing movement without wasting the precious metallic leaf on the backing strip between these two points.

45 Fig. 7 shows a short section of the backing strip of paper carrying its metallic leaf to be deposited.

It is found in the practical use of metallic leaf depositing devices, particularly those of the class designed to work in groups to simultaneously apply a plurality of strips of metallic leaf to the back of books and the like having rounded surfaces that owing to the curvature of the back and the angle at which the device is mounted to be swung in its frame (not shown) the depositing roll must of necessity be rotated backward, after 55 each depositing operation, a short distance from its stopping point each time a new line is started, in order to prevent waste of the precious metal which is being applied, and in order to effect this backward rotating of the depositing roll, it is found of advantage to secure the package roll to its shaft and then rotate this shaft backward to drag the depositing roll backward thru its backing strip to the desired point and in order to accomplish this in a simple and effective way it is found of advantage to lock the package roll to its shaft by some suitable means.

55 In some instances, I may provide a plurality of openings in the side face of the core of the package roll into any one of which the shaft drive member may be pressed by a spring, whereby the roll may be slid laterally against its spring pressure and released from the drive to be rotated independently of the 60 shaft and its gear-operated drive, to adjust the tension of its metallic leaf backing strip independently of the shaft rotation, and the following is a detailed description of the present embodiment of my invention showing one 65 means by which these advantageous results may be accomplished.

65 With reference to the drawings, 10 designates one of the metallic leaf applying devices which is designed to be mounted in a frame (not shown) to be swung on a pivot across the back of a book on to which one or more strips of metallic leaf such as gold leaf or the like is to be deposited. This applying device shown is constructed with a pair of 70 spaced side plates 11 in which are mounted a pair of endways slidable roll-carrying strips 15 having the usual cross bar 15a slidably mounted on an adjusting rod 15b against the tension of a spring 15c, the adjusting rod 15b 75

being screw-threadedly mounted in the head of the leaf applying device and in these strips is rotatably mounted the shaft 12 having a driving pinion 13 fixed to one end and meshing with a gear 14 mounted for movement therewith by means of which this shaft may be rotated when desired. On this shaft is fixed a drive plate 16 by a set screw 17 the plate having a laterally-extending drive pin 18 for the purpose presently described. On this shaft is loosely mounted a package roll of metallic leaf, which roll comprises a core 20 of wood, or other suitable material, on which is wound a length of backing paper carrying the usual layer of metallic leaf such as gold leaf, see Fig. 7.

It is found in practice necessary to provide some practical means by which this roll may be caused to be rotated with this shaft and at the same time to be readily detached therefrom when desired, and to accomplish this result in a simple and practical way, I have herein shown one simple construction which is that of providing one or more openings 21 in the package roll core to receive the pin 18 in the drive plate 16 and in order to yieldably press this drive pin into the selected opening, I have provided a flat spring 22 having one end fixed to one of the plates 15 and its free end engaging the face of the package roll core opposite to that face having the drive pin receiving holes, whereby when it is desired to rotate this roll 19 independently of the shaft to take up the slack of the backing strip, or for any other purpose it is only necessary to slide the roll sideways on its shaft against its spring tension and after rotating the same on its shaft the desired amount, it is released causing the pin 18 to engage another of the several holes 21 in the core and the adjustment is completed.

In the forward ends of these plates 15 the deposit roll 23 is pivotally mounted and about which the backing strip 24 carrying its metallic leaf 25, see Fig. 7, is led and wound from the package roll 19 in the usual way.

By the use of my improved construction the package roll is mounted to be driven by the shaft 12 and yet may be readily detached therefrom when desired for adjustment. Thus, considering Figure 6, when the roll of gold leaf is moved from position A to position B, there will be waste of gold leaf when again applying the roll to a book. The improved keying of the package rolls to the actuating shafts permits positive backward rotation of the package rolls, and the plurality of recesses facilitates positioning and adjustment.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

In a metallic leaf applying device, a pair of separable spaced support plates, spring pressed slide members movably mounted in said plates, a package roll shaft mounted in said slide members, a driving element on said package roll shaft, a friction roll mounted in said slide members, a package roll of metallic leaf rotatably mounted on said package roll shaft and having a recess receiving said driving element, whereby said roll is positively driven by said driving element and manually operable mechanism operatively connected to said package roll shaft.

In testimony whereof I affix my signature.

STUART H. SWALLOW.
